UNITED STATES PATENT OFFICE.

WILLIAM B. PYLE, OF ROBINSON, ILLINOIS.

WATER-CIRCULATING SYSTEM FOR EXPLOSIVE-ENGINES.

1,142,055.

Specification of Letters Patent.

Patented June 8, 1915.

Application filed December 19, 1912. Serial No. 737,729.

To all whom it may concern:

Be it known that I, WILLIAM B. PYLE, a citizen of the United States, residing at Robinson, in the county of Crawford, State 5 of Illinois, have invented certain new and useful Improvements in Water-Circulating Systems for Explosive-Engines; and I do hereby declare the following to be a full, clear, and exact description of the invention, 10 such as will enable others skilled in the art to which it appertains to make and use the same.

This invention relates to improvements in water cooling systems for explosive engines.

15 The principal object of the invention is to provide such a system that a quantity of cool water from a supply tank will be drawn positively through the water jacket at each exhaust of the engine.

20 Another object is to provide a system of such construction and arrangement that cool water from the supply tank will be drawn directly through the water jacket under the action of the exhaust from the engine, and 25 the heated water returned to the tank.

Other objects and advantages will be apparent from the following description and with particular reference to the accompanying drawings.

30 In the drawings the figure is a sectional elevation of my water circulating system.

Referring particularly to the accompanying drawings, 10 represents the cylinder of an explosive engine, which is provided with 35 the usual exhaust pipe 11. The cylinder is also provided with the usual water jacket 12 in connection with which my device is used.

Disposed adjacent the engine is a water 40 supply tank 13, and leading from the lower end of the tank to the lower side of the cylinder, and entering the water jacket, is a conduit 14 for conveying cool water from the tank to the jacket, this conduit 14 entering the jacket of the cylinder near the outer end thereof.

Connected to the water jacket on the upper side of the engine near the rear end thereof is a conduit 15, said conduit extending 50 a suitable distance above the water level of the tank 13, where it extends horizontally as indicated at 16 and is connected to a vertical pipe 17. Located in the pipe 15 just above the cylinder 10 is a check valve 18 55 which opens in a direction away from the cylinder, and in one side of this check valve

is arranged a pet cock 19. At a suitable point between the check valve 18 and the horizontal portion 16 is a return pipe 20, this pipe being arranged and extending horizontally toward and discharging the water into the top of the tank. In this pipe 20 is a valve 21 opening toward the tank. Extending from the exhaust pipes 11 is a pipe 22 and connecting this pipe 22, by means of 60 the union 23, to the pipe 17, is a pipe 24, this pipe being provided with a stop cock 25. By means of the valve the effectiveness of the pull of the exhaust can be regulated.

The operation of the cooling system can 70 be briefly described as follows: The exhaust flowing through the pipe 11 creates a vacuum in the pipes 24, 17, 16 and 15, and causes the water to flow directly from the bottom of the tank 13 through the pipe 14, the water 75 jacket and up the pipe 15. This pipe 15 is of a height sufficient to take a column of water equal to the amount of water which is in the water jacket and which has become hot. Upon closing of the exhaust air will 80 rush into the pipes 22, 17 and 15 and exert pressure on and cause the same to flow back through the pipe 20, into the tank. Return of water into the jacket is prevented by the check valve 18, the pressure of the water 85 opening the valve 21 and permitting the same to pass into the tank.

From the foregoing it will thus be seen that in each exhaust of the engine a fresh supply of absolutely cool water is drawn 90 entirely through the jacket of the engine, the warm or hot water being forced up into the pipe 15 and being prevented from returning into the jacket by the valve 18.

Attention is particularly directed to the 95 fact that applicant does not depend on gravity for the flow of the cold water into the water jacket, but the flow is positive and direct at each exhaust of the engine.

Attention is particularly called to the 100 valve 25. By partially closing this valve the effectiveness of the pull of the exhaust will be reduced. Were the valve to be moved into complete open position, the effectiveness of the pull of the exhaust would be 105 so great that the column of the water raised in the limb 15 might not be relieved of the suction to an extent sufficient to permit it to fall by gravity, the result being the continued suction of water until it flowed 110 through the limb 17 to the exhaust pipe 11. Thus the effectiveness of the system can be

gaged according to the speed of the engine. It will also be noted that the exhaust pipe, as well as the point of connection of the pipe 24 thereto is disposed below the engine cylinder, thereby precluding any possibility of entrance of water into the cylinder.

5 What is claimed is:

The combination with an explosive engine including a water jacket and an exhaust pipe, of a water circulating system therefor comprising a water tank, a conduit connecting the lower end of the tank with the lower side of the water jacket of the engine, an inverted U-shaped conduit extending above 10 the tank and having one limb connected to the upper side of the water jacket and the other end connected to the side of the ex-

haust pipe below the cylinder of the engine, a conduit connecting the first named limb with the upper end of the tank, said first 20 named limb having an upwardly opening check valve below the last named conduit, a check valve in the last named conduit opening toward the tank, and a valve in the second named limb of the U-shaped conduit for 25 controlling the effectiveness of the suction from the exhaust pipe.

In testimony whereof, I affix my signature, in the presence of two witnesses.

WILLIAM B. PYLE.
